UNITED STATES PATENT OFFICE.

EDWARD SMULSKI, OF BROOKLINE, MASSACHUSETTS.

CONCRETE CONSTRUCTION.

1,196,892.

Specification of Letters Patent.

Patented Sept. 5, 1916.

Application filed November 12, 1915. Serial No. 61,097.

To all whom it may concern:

Be it known that I, EDWARD SMULSKI, a citizen of the United States, and a resident of Brookline, Massachusetts, have invented an Improvement in Concrete Construction, of which the following description, in connection with the accompanying drawings, is a specification, like characters on the drawings representing like parts.

10 This invention relates to concrete structures, and among other objects aims to provide a simple and effective reinforcing system therefor.

15 The character of the invention may be best understood by reference to the following description of illustrative embodiments thereof shown in the accompanying drawings, wherein:

20 Figure 1 is a plan of a system of reinforcing elements embodying the invention; Fig. 2 is a section taken on line 2—2 of Fig. 1; Fig. 3, on an enlarged scale, is a section taken on line 3—3 of Fig. 1; Fig. 3^a is a detail to be referred to; Fig. 4 is a plan of a 25 modification comprising a system of circumferential elements for a floor panel; Fig. 5 is a vertical section taken on line 11—11 of Fig. 4; and, Fig. 6 is a vertical section taken on line 12—12 of Fig. 4.

30 Referring to the drawings, in Figs. 1, 2 and 3 are shown columns 1 of concrete supporting a floor slab 3. Heretofore it has been the practice to provide the columns with large flaring caps to distribute the sup-

35 port from the columns to the slab. These caps are usually of unsightly appearance, undesirable from an architectural point of view, and require the use of a considerable quantity of concrete. One of the objects of 40 my invention is to eliminate the necessity for such caps. To accomplish this means is provided for distributing the support from the column to the slab, typified herein in the form of sets of rods 5 above each column

45 and radiating therefrom. Each of these rods may have a vertical portion 7 adjacent the column, a tension reinforcing portion near the upper surface of the slab, and a compression reinforcing portion 9 adjacent the lower surface of the slab. To further contribute to the distribution of the support from the column to the slab and prevent transverse cracks in the slab, rods 11

50 may be introduced therein, each in the form of a loop (Fig. 3^a), extending around the vertical portions 7 of the radial rods 5 and

thereby obtaining a secure anchorage therewith. As shown herein these rods extend to the column, but they may extend across the column if desired.

60

The group of rods 5 and 11 radiating from the column constitute in effect a head for the column which may be within the slab and distribute the support of the column desirably and effectively to the slab, 65 but without unsightly protuberances and with a great saving of concrete.

The depth of the portion of the slab occupied by the reinforcing rods described may vary as desired. This depth may be the 70

same as the depth of the slab or it may be greater than the depth of the slab, and present an outward radial concrete rib or beam 13. Said beam may terminate a short distance from the column and constitute a 75 bracket or it may extend from one column across the slab to the adjacent column as is illustrated by the beam 17. To reinforce this beam, rods 19 may be introduced therein having portions intermediate their ends located in the portion of the concrete adjacent the lower edge of the beam, thereby contributing to the tension strength thereof. The ends of these rods may be bent upward as at 21, and looped about or anchored to 80 circumferential rods to be described and thereby tend to prevent transverse cracks in the slab.

To contribute to the strength of the portion of the slab between columns straight 90 rods 23 may be provided in the slab, some adjacent the upper surface and some adjacent the lower surface thereof and extending transversely of the beam 17. These will desirably strengthen the portion of the slab 95 above the beam and distribute the support from the beam toward the central regions of adjacent panels.

To reinforce the portions of the slab adjacent the beams 17 and the arms of the 100 brackets 13 rods 24 may be introduced into the slab adjacent the lower face thereof and extend substantially parallel to said beams and arms. The ends of these rods 24 may cross at points closely adjacent to the columns and thus desirably occupy and reinforce areas between the arms of the brackets.

To reinforce the portion of the concrete slab above the column a series of circumferential rods 25 may be provided. To 110 strengthen the juncture of the reinforce

- head with the slab additional circumferential rods 25^a may be provided adjacent the lower surface of the slab. To strengthen in tension the lower central region of the slab between the columns, a set of circumferential rods 26 may be provided and groups of diagonally extending rods 27 may extend in crossing and flaring relation transversely to the circular rods 26.
- 10 Referring now to Figs. 4, 5 and 6, the embodiment of the invention there shown comprises columns 61 of concrete having circumferential rods or rings 63 above the same connected by two or more longitudinal rods or stringers 65 extending from column to column adjacent the lower surface of the slab between them, and having upwardly inclined end portions 67 anchored to the rings 63. The intermediate portions of these rods 15 will strengthen the slab in tension and the inclined portions will prevent cracks occurring at the juncture of the slab with the column head. The region of the slab adjacent the stringers 65 may be reinforced by 20 groups of circumferential rods 69 near the lower surface of the slab and covering the area between the reinforce heads of the columns. The rods 69 may conveniently rest upon and be supported by said stringers. 25 To reinforce the central region of the slab between columns a group of circumferential rods 71 may be provided adjacent the lower surface of the slab and stringers 73 may extend diagonally across the slab and 30 35 have upwardly bent ends anchored to the rings 63 referred to. The stringers 73 may be offset or bent slightly at their crossing points and may conveniently support the circumferential rods 71.
- 40 The portion of the slab above each column may be provided with a reinforcing head therein of either the rod or beam type as described, the latter being shown herein. The groups of circumferential rods 45 surrounding the central group of circumferential rods provide simple and strong units which are distributed in and strengthen substantially the entire area of the slab.
- It will be noted that the groups of circumferential members are distributed above the columns, between the columns and in the central region of the slab, and in their overlapping relation reinforce substantially the entire area of the slab. Thus they desirably bind and tie the whole construction together and effectively prevent cracking of the concrete by loads thereon or from expansion and contraction of the concrete produced by temperature changes.
- 50 Having described illustrative embodiments of the invention without limiting the same thereto, what I claim as new and desire to secure by Letters Patent is:
1. The combination of a concrete slab 55 with supporting columns therefor, rings

above said columns, stringers extending between said columns connecting said rings and circumferential members extending transversely to said stringers.

2. The combination of a concrete slab 70 with supporting columns therefor, reinforcing members extending between columns adjacent the lower surface of the slab and having upwardly projecting ends, rings above the columns connected to said ends 75 and groups of circumferential members adjacent the lower surface of the slab extending transversely to said first named members.

3. The combination of a concrete slab 80 with supporting columns therefor, reinforcing means located adjacent the lower surface of the slab in the central region thereof between columns, and groups of circumferential members located adjacent the 85 lower surface of the slab beyond and between the columns and extending into said central region.

4. The combination of a concrete slab 90 with supporting columns therefor, a group of circumferential members located adjacent the lower surface of the slab in the central region thereof between columns, and groups of circumferential members located adjacent the lower surface of the slab, surrounding 95 said central group between and beyond the columns and extending into said central region.

5. The combination of a concrete slab 100 with supporting columns therefor, rings in the slab above the columns, stringers extending from column to column including stringers extending diagonally across the center of the slab between columns, a group of circumferential members for reinforcing 105 the center of the slab and groups of reinforcing members surrounding said first named group.

6. The combination of a concrete slab 110 with supporting columns therefor, reinforcing means above the columns for distributing the support from the latter to the slab, members extending directly between columns, a group of circumferential members located adjacent the lower surface of 115 the slab in the central region thereof between columns, and groups of circumferential members located adjacent the lower surface of the slab beyond and between the columns and extending into said central 120 region.

7. The combination of a concrete slab 125 with supporting columns therefor and reinforcing means for the slab including rings above the columns, stringers connecting the 12 rings and groups of circumferential members resting on the stringers.

8. The combination with a concrete slab 130 of supporting columns therefor, and reinforcing means for said slab including a

group of circumferential members located adjacent the lower surface of the central region of the slab between the columns, and groups of circumferential members located 5 adjacent the lower surface of the slab between the columns and overlapping said central group.

9. The combination with a concrete slab of supporting columns therefor, and reinforcing means for said slab including reinforcing means adjacent the upper surface of the slab above the columns, reinforcing means for the central region of the slab, and groups of circumferential members located 15 adjacent the lower surface of the slab between said columns about said central reinforcing means.

10. The combination with a concrete slab of supporting columns therefor, and reinforcing means for said slab including circumferential members above the columns adjacent the upper surface of the slab, reinforcing members connected to said circumferential members and extending between 25 columns directly and diagonally, a group of reinforcing members located adjacent the lower surface of the central region of the slab transversely to said diagonal members, and groups of circumferential members located 30 adjacent the lower surface of the slab between columns and overlapping said central group.

11. The combination with a concrete slab of supporting columns therefor, and reinforcing means for said slab including members 35 63 above the columns, stringers 65 connecting said members, groups of circumferential members 69 located adjacent the lower surface of the slab between and beyond 40 said columns and extending transversely to said stringers, diagonal stringers 73 connected to said members 63, and a group of circumferential members 71 located adjacent the lower surface of the slab in the central region thereof and extending transversely to said diagonal members.

12. The combination with a concrete slab of supporting columns therefor, and reinforcing means for said slab including circumferential members 63 located adjacent 50 the upper surface of the slab above the columns, stringers 65 and 73 connected to said circumferential members, and groups of circumferential members 69 and 71 located ad-

jacent the lower surface of the slab transversely to said stringers and distributed to reinforce substantially the entire area of the slab between said columns.

13. The combination with a concrete slab of supporting columns therefor, and reinforcing means for said slab including members extending between columns directly and diagonally, a group of circumferential members located adjacent the lower surface of the central region of the slab transversely 55 of said diagonal members, groups of circumferential members adjacent the upper surface of the slab above said columns, radial reinforcing members located adjacent the upper surface of the slab transversely to the 60 circumferential members above the columns, and groups of circumferential members located adjacent the lower surface of the slab between columns and overlapping the groups of circumferential members above 65 the columns and in the central region of the slab.

14. The combination with a concrete slab of supporting columns therefor, and reinforcing means for said slab including groups 70 of circumferential members 43 adjacent the upper surface of the slab above the columns, groups of circumferential members 69 between columns adjacent the lower surface of the slab, and a central group of circumferential members 71 in the central region and adjacent the lower surface of the slab, said groups being distributed to cover substantially 75 the entire area of the slab.

15. The combination with a concrete slab 80 of supporting columns therefor, and reinforcing means for said slab including circumferential members 43 located adjacent the upper surface of the slab above the columns, stringers 65 and 73 between the columns, and groups of circumferential members 69 and 71 adjacent the lower surface 85 of the slab, said groups of circumferential members being distributed to reinforce substantially the entire area of the slab.

In testimony whereof, I have signed my name to this specification, in the presence of two subscribing witnesses.

EDWARD SMULSKI.
